UNITED STATES PATENT OFFICE.

THOMAS POYSER, OF SAN FRANCISCO, CALIFORNIA.

SELF-ACTING BLOW-PIPE LAMP, SOLDERING-IRON HEATER, AND PAINT-BURNER.

SPECIFICATION forming part of Letters Patent No. 257,380, dated May 2, 1882.

Application filed February 21, 1882. (No model.)

To all whom it may concern:

Be it known that I, THOMAS POYSER, a citizen of the United States, residing in the city and county of San Francisco, and State of California, have invented a new and useful Combined Self-Acting Blow-Pipe Lamp, Soldering-Iron Heater, and Paint-Burner, of which the following is a specification.

The nature of my invention consists in the construction, combination, and arrangement of a self-acting blow-pipe, soldering-iron heater, and paint-burner, and combining the same in a simple and convenient tool or implement, and will be more clearly understood by reference to the accompanying drawings and the references marked thereon.

Figure 1 is an elevation showing the implement complete when the whole is joined as used in soldering. Fig. 2 is a similar view of the same arranged for paint-burning, or as used as a blow-pipe. Fig. 3 is a plan view of the same arranged for the purpose of showing and fully explaining the operating parts, and Figs. 4 and 5 are views of detached parts.

The following is the construction of the same: A represents a can or tight vessel of convenient size for handling; B, the wick-tube; C, the cap; D, the combustion-tube as shown in Fig. 1, for soldering; E, the combustion-tube as shown in Fig. 2; F, the recess, and G the jet-perforation. I construct the can A of sheet metal, strong and durable, and the wick-tube of gas-pipe, or of any suitable tubing for strength and durability; and the cap C is the ordinary blind cap for gas-pipe with the recess F and perforation G formed to produce a clear jet or fine solid stream of fluid forced through it. The wick W is placed in the center of the wick-tube B, extending from the upper end of the same to the bottom of the can. The upper portion of the wick-tube B is packed in around the wick W with cotton wicking or other porous or fibrous substance about half-way down the tube, as shown in the sectional drawing, Fig. 3. The wick and packing do not have to be replaced after being once placed, as the heat to which they are subjected does not injuriously affect them. In filling the can A the wick-tube B is unscrewed and taken out, and the gasoline is poured in through the hole left by the removal of the tube.

My reason for not having another opening

for filling is that persons might fill the can while burning, or it might leave a means of escape for the gas.

The tube B is fitted gas-tight in the can. The combustion-tube used for soldering and paint-burning is constructed of sheet metal cut in the shape shown in Fig. 5. The notches P in the sides are cut to form a diamond-shaped opening for the supply of oxygen from the air for combustion, as will be shown. This plate or sheet is rolled to fit the cap of the wick-tube and to form the combustion-tube E, as shown in Fig. 2. The combustion-tube D (shown in Fig. 1) is either formed by rolling in the same way as just described or in any other suitable way to form the tube shown, having the two openings O and P, Fig. 4. It should be made firm and solid to form a good setting for the soldering-bit.

The following is the operation of the same: The can A being supplied with gasoline or other light burning-fluid, the wick draws the oil up into the tube B, saturating the packing V and supplying the cavity or recess F and the fine perforation G, which, when touched with a match, ignites and burns quietly, gradually heating the combustion-tube D and wick-tube B, which creates pressure by gas forming in the wick-tube and can, and forces a steady jet or fine stream through the perforation G, as shown in Fig. 2. The jet passing up into the center of the combustion-tube is burned, increasing its volume to fill the combustion-tube and to retain the velocity of the stream or jet. By this means a draft through the openings P supplies the necessary oxygen for complete combustion. The heated column or flame is thrown out from three to twelve inches in ordinary operations, like the blaze from a powerful blow-pipe. By adjusting the combustion-tube the intensity of the heat is regulated, as by raising the same and leaving a space or chamber between the cap C and the lower part of the opening P the heat-conducting power is decreased between the flame and the pipe D, thus increasing or decreasing the heat and consequent pressure and blast as required.

When used as a soldering-iron heater the can is operated as before described, the copper bit extending down into the opening O sufficiently to be surrounded by the heated column or blaze. The combustion-tube being drawn down so as

100

to bring the opening P close to the cap C, and also the combustion-chamber, which commences just above the opening P, the heat is rapidly conducted to the wick-tube, forming 5 gas and increasing the pressure, so as to force a clear stream or fine jet of gas at a high velocity, which, expanding as it ignites in the combustion-chamber and continuing its 10 velocity, blows exactly as a blow-pipe and heats the copper bit quickly to the required heat, when it can be regulated by adjusting the combustion-chamber as has been shown. When used for burning off paint from painted 15 surfaces this device presents great advantage in the fact that it may be held so as to throw the flame in any required direction, the whole implement being perfectly portable and as simple and convenient to handle as any other hand-tool for soldering or heating, and when used in 20 the place of the blow-pipe the flame can be directed perfectly in any required direction without diminishing the force of the blast, as when pointed downward the blast is not at all diminished, depending wholly upon the velocity of the 25 stream injected into the center of the combustion-tube.

I do not confine myself to any particular dimensions or weight of material, as in this particular the construction may be varied to suit the character or magnitude of the heating or 30 soldering to be effected.

Having thus described my invention, what I claim, and desire to secure by Letters Patent, is—

1. The can A, having the wick-tube B and cap 35 C, with open reservoir or recess F and perforation G, and the wick W and packing V, in combination with the combustion-tube E, having the single side opening, P, to use as a portable blow-pipe and heater and burner, substantially 40 as and for the purposes set forth.

2. The can A, having the wick-tube B and cap C, with open reservoir or recess F and perforation G, and the wick W and packing V, in combination with the combustion-tube D, with 45 the two side openings, O and P, as used for soldering, substantially as and for the purposes set forth.

THOMAS POYSER.
